UNITED STATES PATENT OFFICE.

ANDREW B. LIPSEY, OF WEST HOBOKEN, NEW JERSEY, ASSIGNOR TO
WILLIAM BELL, OF NEW YORK, N. Y.

DISINTEGRATING-MACHINE.

SPECIFICATION forming part of Letters Patent No. 243,928, dated July 5, 1881.

Application filed October 12, 1880. (No model.)

To all whom it may concern:

Be it known that I, ANDREW B. LIPSEY, of West Hoboken, in the county of Hudson and State of New Jersey, have invented certain new and useful Improvements in Disintegrating-Machines, of which the following is a specification.

My invention relates to disintegrating mills or machines in which are arranged circular series of beaters, the beaters of alternate series being attached to and projecting from a rotary disk, while the beaters of intervening series are attached to and project from a stationary case, or from a disk rotating in an opposite direction to the disk first named. These beaters commonly consist of pins which are separately attached to the disk, each by means of a separate nut; and the object of my invention is to provide for making and attaching the beaters at a much less cost than is now possible, and especially to enable the several circular series of beaters to be secured much nearer together than when each beater is secured by means of a separate nut.

To this end my invention consists in the combination, with a circular series of beaters for a disintegrating-machine, of an annular or segmental strip integral with the beaters and from which they project. The disk may be provided with annular grooves in its face or faces, and the strip or strips of metal, after being bent or produced in a circular form, are inserted into said grooves, and held by means of screws, bolts, or other like means. In order to increase the strength of the fingers or bars which form the beaters, their free ends are connected by a continuous bar, and the whole may be conveniently formed by simply punching holes in a strip of sheet or plate metal of proper width and then bending it into the form of a ring or a segment of a ring.

The invention also consists in the combination, in a disintegrating-machine, of a disk provided with concentric annular grooves, annular or segmental strips of metal, provided with openings the sides of which form beating-surfaces, inserted into said grooves, and means for holding them therein.

In combination with a rotary disk provided

with beaters of the kind described may be used a second disk rotating in the opposite direction to the first-mentioned disk, and carrying beaters of the same character, which intervene between the beaters upon the first-mentioned disk; or a single rotary disk and beaters may operate in connection with a stationary case and stationary beaters.

In the accompanying drawings, Figure 1 represents a vertical section through a machine embodying my invention upon a plane parallel with its shaft. Fig. 2 represents a plan of a strip of metal punched so as to form the beaters. Fig. 3 represents a longitudinal section through said strip. Fig. 4 represents a plan of a strip of slightly-modified form, and Fig. 5 represents a transverse section of the shaft and deflector of my machine.

Similar letters of reference designate corresponding parts in all the figures.

A designates the case of the machine, which is of approximately cylindric form, and which is supported upon a bed, B.

C designates a shaft mounted in bearings D upon the bed B, and adapted to be rotated rapidly by means of belts passing over pulleys C', or by other means.

E designates a disk rigidly fixed upon the rotary shaft C, and arranged centrally within the case A.

To the disk E, upon opposite sides thereof, are attached beaters *a*, arranged in concentric circular series, the beaters upon one side of said disk preferably being intermediate between the series of beaters upon the opposite side thereof.

To the interior of the case A, upon opposite sides, are attached stationary beaters *b*, also arranged in circular series and placed between or intermeshing with the rotary beaters. The beaters *a* and *b* consist of fingers or bars, which project laterally from and are made integral with or in the same piece with continuous strips or pieces *a'*. The strips *a'* supporting the beaters are preferably attached to the disk and case by forming annular grooves *c* in the sides of the disk and case, and in these grooves the strips *a'* are inserted and secured by means of bolts or screws. The beaters *a*

and *b* might be made of comparatively thick metal and have free outer ends; but in order to greatly strengthen the beaters I preferably connect their free ends by means of continuous bars *a*², which are also made integral with the beaters.

In the manufacture of the beaters a strip of sheet or plate metal of proper width and thickness is cut or punched out into the form shown in Fig. 2, the beaters *a* being formed by cutting out holes *d* at a uniform distance apart, the metal between them constituting the beaters.

In Figs. 1, 2, and 3 the beaters *a* and *b* are shown as having smooth straight edges; but in order to increase their efficiency I may make the edges serrated, or of irregular or zigzag outline, as shown in Fig. 4, so as to act upon the material to be reduced with better results.

In the operation of my machine the material to be disintegrated is introduced through the inlet-openings or hoppers *F*, and by the centrifugal force generated by the rotation of the disk is thrown outward and successively operated upon by the several series of beaters as it passes through or between them to the outer circumference of the case, where it is delivered through an outlet or discharge-chute, *G*.

It will be observed that the openings *F*, through which the material is introduced into the machine, are over the shaft *C*, and to guide or direct the material down each side of said shaft I may attach to the inner sides of the case, just under said openings, inverted *V*-shaped deflectors arranged above the shaft, as best seen in Fig. 5. Instead of being *V*-shaped, the said deflector might be of convex form.

By my invention I am enabled to provide disintegrating-machines with beaters of my improved character at very much less cost than they could be provided with separate beaters each secured in the case separately. The beaters of each circular series being connected with each other by a continuous strip or bar, *a*', there is much less liability of their being bent or deflected relatively to adjacent beaters than there is where each beater is made and attached separately, because the bar *a*' forms a brace or stay to each beater, and when the bar *a*² is used to connect their outer or free ends it forms an additional brace or stay to them.

Owing to the circular form of the strips or bars *a*' *a*², the beaters are braced against deflection toward or from the center of the machine. This result is still further attained by inserting the strips or bars *a*' in the grooves in the disk or case, as above described, and the screws or bolts are only necessary for holding said strips or bars in said grooves; hence a very much less number of screws or bolts are necessary than if the beaters were each secured separately.

In case the beaters *a* should be necessarily of considerable length they may be still further strengthened by connecting them by an

intermediate bar or bars between the strips or bars *a*' *a*².

It will be clearly understood that in all cases the edges of the beaters *a*, which are the sides of the openings between them, constitute the beating-surfaces, and, if desirable, I may form beating-surfaces by punching or forming holes or openings of any form in a strip of metal, the sides of the openings constituting the beating-surfaces.

The strips, with the beaters attached, instead of being formed by punching or cutting sheet or plate metal may, perhaps, be more advantageously cast of steel or other metal in circular form.

It is obvious that when the beaters are formed with the continuous bars *a*' *a*², if one edge of the beaters becomes much worn, the strips may be reversed, the bar *a*² being inserted and secured in the groove instead of the strip *a*', thus presenting new edges of the beaters for operation and producing the same effect as if the shaft were rotated in the opposite direction. The heaviest work comes upon a certain part or parts of the circumference of the machine, and consequently the stationary beaters at such part or parts are subjected to greater wear than the others. If the screws or bolts which secure the stationary beaters in the grooves be placed equidistant from each other, the beaters of each stationary series may be shifted or turned so as to bring the beaters which are little worn at the part or parts where there is the most wear.

What I claim as my invention, and desire to secure by Letters Patent, is—

1. The combination, with a circular series of beaters for a disintegrating-machine, of an annular or segmental strip integral with the beaters, and from which they project, substantially as and for the purpose specified.

2. The combination, with a disk for a disintegrating-machine provided with concentric annular grooves, of annular or segmental strips of metal inserted into and secured in said grooves and circular series of beaters projecting from and made integral with said strips, substantially as and for the purpose specified.

3. The combination, with a circular series of beaters for a disintegrating-machine, of annular or segmental strips of metal, made integral with said beaters, and between which said beaters extend, substantially as and for the purpose specified.

4. The combination, in a disintegrating-machine, of a disk provided with concentric annular grooves, and annular or segmental strips of metal, inserted into and secured in said grooves, and provided with openings the sides of which form beating-surfaces, substantially as specified.

ANDREW B. LIPSEY.
